BEVERAGE SERVER

Glenn B. Beckman, Corning, N.Y., assignor to Corning Glass Works, Corning, N.Y.

Filed Mar. 19, 1973, Ser. No. 342,762

Term of patent 14 years

Int. Cl. D7—01

U.S. Cl. D7—59

Fig. 1

Fig. 2

Fig. 3

Fig. 4

FIG. 1 is a side elevational view of a beverage server embodying my new design with the opposite side being a mirror image.

FIG. 2 is a front elevational view with a portion of the stopper shown in cross-section.

FIG. 3 is a rear elevational view.

FIG. 4 is a top plan view.

I claim:

The ornamental design for a beverage server, as shown and described.
